UNITED STATES PATENT OFFICE.

PRESLY J. FICKINGER, OF CONNEAUT, OHIO.

STOCKING-BRIDGE.

1,319,996.

Specification of Letters Patent. Patented Oct. 28, 1919.

Application filed June 11, 1918. Serial No. 239,470.

To all whom it may concern:

Be it known that I, PRESLY J. FICKINGER, a citizen of the United States, a resident of Conneaut, county of Ashtabula, and State of Ohio, have invented certain new and useful Improvements in Stocking-Bridges, of which the following is a specification.

My invention relates to stocking cranes for handling bulk material, the chief features of novelty residing in the means for driving the crane along its tramway and means for holding the crane against the movement along the tramway.

Heretofore considerable difficulty has been experienced in effectively holding stocking cranes from being blown along their tramways by high winds. At night and other times when these cranes are unattended, windstorms have often blown them along the tramway and have at times caused them to travel to the end of the tramway and topple over and cause considerable damage. Various means have been tried to securely hold these stocking cranes in place, one of which was to provide brakes on the axles of the track wheels but in practice it was found that even though the wheels were locked if a high wind came up it simply skidded the whole structure along the tramway. These cranes are of gigantic sizes, the one illustrated having a bridge of over five hundred and fifty feet in length and reaching a height of one hundred and eight feet from the track rails to the top of the upperchord of the bridge. It will, therefore, be appreciated that the structural framing of the bridge presents an appreciable area for wind pressure to act upon.

The objects and advantages of the invention will be clear from the following description and the accompanying drawings in which,—

Figure 1 is a conventional side elevation of a stocking crane looking along the tramway;

Fig. 2 is a diagrammatic plan of Fig. 1;

Fig. 3 is a sectional view on the line 3—3 of Fig. 1 showing one of the supporting legs for the bridge of the crane;

Fig. 4 is a section on the line 4—4 of Fig. 1 showing the other supporting leg for the bridge of the crane;

Fig. 5 is an enlarged detail of the driving mechanism for the crane being a view substantially on line 5—5 of Fig. 1;

Fig. 6 is a sectional view on the staggered line 6—6 of Fig. 5;

Fig. 7 is a detail section on the line 7—7 of Fig. 5.

In the drawings the bridge 1 of the crane 60 supports the usual traveler or crane trolley 2 from which the clam shell bucket 3 or other loading device is operable. The bridge is supported at one end by a pair of legs 4 and at the other end by a tower 5 consisting of suitably braced legs 6 and 7. The driving and holding mechanism for the crane is secured to the box girders 8—8—8 forming the lower supports for the legs 4 and the tower 5, and is conveniently 70 arranged in multiple as shown in Figs. 1, 3 and 4, there being two driving units A and B for the leg 4 as shown in Fig. 3 and also two driving units C and D for each of the legs 6 and 7 of the 75 tower 5 as shown in Fig. 4. As these units are all practically identical in construction it is deemed sufficient herein to only describe one in detail.

The several box girders 8 which support the legs 4 and the tower 5, are provided with suitable trucks 9 having track wheels 10 for movably supporting the crane on the track rails 11 of the crane runway which are suitably secured to longitudinally extending 80 footings 12 of the runway. Firmly secured to each of the footings 12 is a rack 14 which is adapted to coöperate with the driving mechanism carried by the crane. This rack is preferably, although not necessarily, constructed of a pair of longitudinally extending parallel bars 15 and 16 (Figs. 5 and 6) having transverse rods 17 passing therethrough and secured as shown in Figs. 5 and 6. This construction is simple and inexpensive to manufacture and yet can readily be made very strong to withstand the hard usage to which such a rack is subjected. The cross rods 17 are of rolled stock and present a smooth working face to the teeth of the 100 coöperating gear of the driving mechanism and in this respect are more satisfactory than the cast teeth of an ordinary rack would be. When the rods become badly worn or damaged they can be easily driven out and new ones substituted therefor. As these racks in practice are several hundred feet long the advantage of this construction will be appreciated by those skilled in this art.

The driving units which coöperate with the rack above described each include a bull pinion 18 which is carried by a shaft 19 supported in suitable bearings 20—20 carried by brackets 21—21 which are secured to plates of the box girder 8. The bull pinion 18 is driven by a shrouded gear 22 integrally formed with a gear 23 both being carried by the shaft 24 which is journaled in suitable bearings 25—25 supported in the upper part of the bracket 21. A shaft 26 also journaled in suitable bearings carried by the bracket 21 has secured thereto a driving gear 27 which meshes with the gear 23. 5 A worm wheel 28 also secured to the shaft 26 is driven by a worm 29 carried by a shaft 30 journaled in suitable bearings within the worm housing 31. A brake drum 32 is secured to the shaft 30 and associated therewith is a band brake comprising a strap 33 having one end secured to a fixed pin 34 and its opposite end to a pin 35 of a brake lever 36. The brake lever is pivoted at 37 to a supporting bracket 38 which is secured to 10 the underside of the box girder 8. The lever 36 has an extended arm 39 adapted to support the adjustable weight 40. A solenoid 41 is secured in any suitable manner to the box girder 8 and the core thereof is 15 connected by a link 42 with the arm 39 of the brake lever. The solenoid 41 of each unit is energized at all times that the driving motors for the crane are running and therefore its core is attracted upwardly 20 and acts to hold the brake lever and band in such position that the brake drum 32 can freely rotate. If for any reason the circuit of the motors is broken the solenoid core of each unit will be de- 25 energized and the counterweight 40 will automatically drop and thereby exert a braking pressure on the drum 32 which will act to prevent any movement of the gearing above described and therefore hold the entire crane in a fixed position due to the engagement of the teeth of the gear 18 with the rods 17 of the rack. 30

The displacement ratio between the worm 29 and the gear 18 is so enormous that it 35 will readily be seen that a comparatively small amount of pressure on the brake drum is required to overcome the tendency of the crane to move along the runway.

The shaft 30 is connected by means of any 40 approved form of self alining coupling 43 with the shaft 44 of the driving motor 45, which is carried by a suitable sub-frame 46 secured to the box girder 8.

In operation when it is desired to move 45 the crane along the runway suitable switches are manipulated to supply current to the several motors 45 carried by the box girders 8 which support the bridge of the crane. As the solenoids 41 are connected in circuit 50 with the motors they are thus energized and

release the brakes 32. The motors operating through the train of gearing above described cause the bull pinion 18 to traverse the rack 14 and thereby propel the crane along the runway. 70

All of the motors 45 of the separate driving units are interconnected electrically but any one of them is capable of delivering enough power to drive the crane. It is advantageous to have the driving mechanism 75 arranged in separate units so that if any breakage occurs or any of the parts fail to operate properly the remaining units will be in reserve to act either as a propelling or a holding means. 80

When the motors are shut off it will readily be seen the solenoids of all the different driving units will be deenergized as above described and the counterweights 40 will exert a braking action on the drums 32, the 85 pressure acting through the reduction gearing described effectively and positively locking the crane against movement along the runway.

Instead of using an automatically operating brake I may use a simple hand brake with suitable locking devices to hold it in different operative positions. 90

By the utilization of the driving mechanism herein disclosed, I am able to effectively lock the crane against the highest wind pressure developed in this locality, and am also able to drive the crane against a head wind. As ordinarily constructed the weight of the crane, enormous as it is 95 in a structure of this size, is not sufficient to provide adequate traction between the track wheels to move the crane against a strong head wind, nor to prevent it from 100 skidding along the tramway before a high 105 wind even through the wheels be locked.

Although I have described with great particularity certain structural details of the embodiment of the invention herein shown, it is not to be construed that I am limited 110 to such a construction, as various changes may be made by those skilled in the art without departing from the spirit and scope of the invention as defined in the subjoined claims. 115

What I claim is:—

1. A stocking crane comprising an overhead bridge having a trolley movably mounted thereon, legs for supporting said bridge adjacent to the ends thereof, wheeled trucks on the lower ends of said legs, track rails forming a runway for said trucks, racks alongside said track rails, driving means on the said stocking crane coöperating with said racks to positively move the 125 crane along the runway, said driving means coöperating with said racks to prevent skidding of the crane on the runway, and a brake for locking said driving mechanism, said brake being adapted to operatively engage 130

with the driving mechanism when the driving mechanism is not operating to actuate the crane.

2. A stocking crane comprising an overhead bridge having a trolley movably mounted thereon, legs for supporting said bridge adjacent to the ends thereof, wheeled trucks on the lower ends of said legs, track rails forming a runway for said trucks, a fixed rack secured to the runway, a plurality of separate driving units carried by said crane and arranged to coact with said rack to positively propel the crane along the runway against the wind pressure on said bridge, and a brake associated with said driving units arranged to prevent movement of the driving units when the driving motors of said units are stopped.

3. A stocking crane comprising an overhead bridge having a trolley movably

mounted thereon, legs for supporting said bridge adjacent to the ends thereof, wheeled trucks on the lower ends of said legs, track rails forming a runway for said trucks, operating means for propelling said crane along said runway, said means including racks forming fixed members on the runway whereby said bridge is positively actuated in traversing the runway and is held against skidding on the runway, and driving means operatively connected to the wheels of said trucks and arranged to engage with said racks to positively propel a bridge along the runway, said driving means including a worm and having braking means coacting with said worm to prevent movement of said crane by wind pressure on said bridge.

In witness whereof, I have hereunto signed my name.

PRESLY J. FICKINGER.
